UNITED STATES PATENT OFFICE.

JOHN H. RICHARDSON, OF MELROSE HIGHLANDS, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

LAST-PULLING MACHINE.

1,398,344.

Specification of Letters Patent. Patented Nov. 29, 1921.

Application filed September 27, 1917. Serial No. 193,599.

To all whom it may concern:

Be it known that I, JOHN H. RICHARDSON, a citizen of the United States, residing at Melrose Highlands, in the county of Middlesex and State of Massachusetts, have invented certain Improvements in Last-Pulling Machines, of which the following description, in connection with the accompanying drawings, is a specification, like reference characters on the drawings indicating like parts in the several figures.

This invention relates to improvements in machines for separating shoes and their lasts. The invention is shown as embodied in a last pulling machine of the general type described and illustrated in United States Letters Patent No. 1,203,571, granted Nov. 7, 1916, upon the application of John M. Benjamin.

As previously constructed, last pulling machines of this type have included a spring auxiliary 2 and coöperating with the last pulling mechanism and arranged to be tensioned during the early stages of last and shoe separation responsively to the resistance offered by the counter portion of the shoe to the lengthwise thrust given the last by said last pulling mechanism partially to reduce said thrust to prevent excessive strain 30 against the back seam and subsequently to impel the last lengthwise of the shoe when the bottom of the last heel clears the top of the shoe counter.

This auxiliary spring, in machines as previously constructed, acts against a bell crank lever to which a last carrier is attached. The resistance offered by the heel end of the shoe to lengthwise heelward thrust of the last as the last heel is moved 40 out of the heel end of the shoe, reacts against said last carrier, causing said carrier to turn said bell crank lever against the action of the spring which yields and permits said turning movement, thereby reducing and 45 relieving the lengthwise thrust given the last heel against the shoe counter by the action of the last pulling mechanism. This arrangement has proven very satisfactory in factory use generally. In a few instances, 50 however, the strain upon the forepart of the shoe upper at the throat of the vamp or the ball portion of the upper has caused the upper materials to be "broken out."

An important feature of the present invention consists in novel means auxiliary to and coöperating with the last and shoe separating mechanism to augment the lengthwise relative thrust given by said mechanism to the last heel and shoe counter at a point during the relative vertical movement of the last heel and shoe counter to clear each other to reduce the strain against the forepart of the shoe upper or throat of the vamp. The augmented lengthwise thrust is preferably only substantially momentary and by the present invention may be timed to occur when the greatest strain would otherwise be placed on the upper at the ball or vamp throat. Preferably, the means for augmenting the lengthwise thrust is adjustable to cause said thrust to occur at variably predetermined times in the cycle for varying conditions and constructions of shoes. Manifestly, shoes will differ in shape and construction and under these conditions means for varying the time when the lengthwise thrust is augmented is a substantial desideratum.

An additional feature of the invention consists in novel means auxiliary to and coöperating with the last and shoe separating mechanism and effective during the initial stage of last and shoe separation, to reduce relative lengthwise thrust of the last heel and shoe counter and subsequently effective at a determinate point to augment said relative lengthwise thrust to relieve strain against the forepart of the shoe upper. As shown herein, an abutment is fixed to the machine frame and is engaged by a relatively movable abutment member connected with and moved by the last pulling mechanism and engaging the fixed abutment at a subsequent and determinate point in the last pulling operation positively to arrest or stop said thrust reduction and to augment the thrust of the last lengthwise heelward against the counter portion of the shoe. This augmentation of thrust is substantially momentary only, the continued movement of the last pulling mechanism sliding the movable abutment member from coöperative engagement with the fixed member. The reduced lengthwise thrust enables the last to be started out of the shoe and by the time the last has been moved sufficiently to cause

substantial strain against the throat of the vamp, the lengthwise thrust is augmented by the coöperation of said abutments to relieve such strain.

5 The illustrated machine embodies mechanism in the form of a plunger, a pivotally attached bell crank lever, and a last carrier pivotally attached to the upper arm of the bell crank lever for effecting movement of 10 the last holding means to move the last from the shoe in a generally diagonally rearward direction relatively to the shoe, with auxiliary means in the form of an abutment plate depending from the lower 15 arm of the bell crank lever and moving with said lever and plunger to engage a fixed abutment on the machine frame, said engagement moving the bell crank lever in a direction to cause said mechanism to augment the lengthwise thrust of the last heel 20 against the shoe counter at a predetermined point in the movement of the last carrier to effect removal of the heel of the last from within the counter portion of the shoe.

25 In another aspect, the invention presents as a further feature auxiliary means as shown, said movable abutment member co-operating with the mechanism and arranged for adjustment to increase the relative 30 lengthwise component of the separating movement of the last and shoe effected through the last pulling mechanism at variably predetermined points in the last and shoe separating movement of said mechanism. This auxiliary means may coöperate 35 with the last pulling mechanism independently of a spring means such as previously described and may be adjusted to increase the lengthwise component of last movement 40 before the last heel clears the top of the shoe counter so as to relieve strain on the vamp or subsequently to this point in the operation, as for example, when the last heel has cleared the top edge of the shoe counter so as 45 to provide an accelerated lengthwise last movement which, in the case of high shoes, will overcome any resistance offered by the back stay portion of the top of a high shoe.

50 These several features of the invention will be more fully understood from the following description, in connection with the accompanying drawings which show an illustrative embodiment of the invention, and will then be particularly pointed out in 55 the claims.

Figure 1 of the drawings is a view in side elevation of a last pulling machine of the described type embodying the present invention; and

60 Figs. 2 to 5, inclusive, are diagrammatic views illustrating the action of the improved last pulling mechanism in successive stages of last and shoe separation.

65 The illustrative machine embodies the essential characteristics of the last pulling

machine of the Benjamin patent previously referred to, and therefore, as to general construction and operation need only be described briefly.

A heavy upright column 2, designed to 70 rest upon a floor or other support, is formed with bearings for a power shaft 4 driven through a clutch member 8 when engaged with a continuously rotating pulley 6 loose on said shaft. The clutch is thrown in by 75 depressing a treadle 10 which, through suitable connections causes a connected cam shaft 12 to be turned through a half revolution (representing one cycle of the machine) and automatically stops the shaft at the end of 80 said half revolution. The cycle of operation may, obviously, be repeated by again depressing the treadle 10.

Rotation of shaft 4, through worm gearing 14—16 turns the cam disk 18 on cam 85 shaft 12 through a half revolution, during the first part of which a positioned shoe is clamped between opposed counter grippers; the last within the shoe being subsequently removed from the shoe by certain mechanism 90 operated from the power shaft. The counter gripping means may or may not be, but as illustrated are, similar to the counter grippers and their associated controlling mechanism described and claimed in an application filed by M. F. Brogan, Serial No. 192,954. These or other suitable counter grippers are indicated generically by dotted lines in the diagrammatic showing in Figs. 2—5 inclusive.

100 In machines of the described type and in the illustrative machine, the initial movement of the cam 18 operates through a bell crank lever 20 and a plunger 22 to close the counter grippers against the opposite sides 105 of the counter portions of the shoe which is positioned between the grippers by the operator prior to the starting of the machine. Subsequently, the cam 18 is effective to cause certain mechanism to pull the last from the 110 gripped shoe.

The last with its shoe is mounted upon a heel pin 24 upstanding from a carrier arm 26, the rear end of which is pivotally secured 115 to the upper arm 28 of a bell crank lever pivoted to the upper end of a plunger 30. After the operator has mounted the last and shoe upon the carrier arm, this arm is swung upwardly by the operator to position the shoe in coöperative relation to the counter grippers. The plunger 30 is guided for movement vertically of the machine frame and is pivoted at its lower end to the forward end of a supporting lever 32 fulcrumed at its rear end at 34 and normally upheld by a 120 counterweight 36. This lever 32 is pivotally connected at a point between its ends to a thrust bar 38, whose forked upper end embraces the hub of a double-armed cam on the 125 cam disk 18, as in the Benjamin patent previ- 130

ously referred to. In the operation of the machine, the thrust bar 38 is moved downwardly by said double-armed cam subsequently to the closing of the counter grippers 5 and is effective to move downwardly the plunger 30 to pull the last from the gripped shoe. The pivotal points of connection of the carrier arm 26 to the bell crank lever 28 and of the bell crank lever 28 to the plunger 10 30 are in vertical planes located rearwardly of the heel end of the gripped shoe. As the plunger descends, there is, therefore, a lengthwise heelward thrust exerted by the heel of the last against the counter portion 15 of the shoe.

This thrust, unless otherwise controlled, may be sufficient to impose excessive strain upon the back seam at the rear extremity of the counter portion of the shoe so as to insure the shoe in extracting the last. By this invention, however, this lengthwise thrust is so controlled by auxiliary mechanism cooperating with the main last pulling mechanism as to prevent injury to the shoe. Accordingly, the lower arm 40 of the bell crank lever has pivoted thereto the upper end of a rod 42, the lower end of which is reduced in diameter and has a free sliding fit with lateral play in a tubular guide 44 carried at 25 the forward end of a bracket 46 which, in turn is fixed to the plunger 30 adjacent to its lower end. A coiled spring 48 is sleeved upon the rod 42 between the tubular guide 44 and an adjustable abutment or throw back 30 plate 50 threaded upon the enlarged and threaded upper end of the rod 42, a check nut being preferably employed to lock the plate in adjusted position.

The abutment or throw back plate 50 is 40 designed to engage its edge surface for a short time, or substantially momentarily with the edge portion of a shelf or abutment plate 52 outstanding from a bracket 54 serving also as a guide for the plunger 30 and 45 rigidly secured between suitable projections from the face of the column 2. Since the bell crank lever, rod 42, guide 44 and bracket 46 are moving downwardly with the plunger 30, the engagement of the throw back plate 50 with the abutment plate 52 will cause the 50 upper arm 28 of the bell crank lever to be swung rearwardly as the plunger continues to descend, exerting augmented lengthwise heelward thrust of the last heel against the shoe counter. The adjusted position of the 55 plate 50 predetermines the point in the last pulling operation when this augmented lengthwise heelward thrust becomes effective. The coiled spring 48 sleeved upon the rod 60 42 is intended to reduce the lengthwise heelward thrust of the last heel against the shoe counter during the initial portion of the movement of the last heel out of the counter portion of the shoe, so as to enable the last 65 to be easily started out of the shoe and to

follow the contour of the counter at the rear extremity of the shoe without exerting excessive strain against the counter and back seam. Subsequently, the throw back plate 50 engages the shelf 52 and is effective to prevent further thrust-relieving yield of the bell crank lever and as the plunger continues to descend, acts to swing the bell crank lever reversely to augment the lengthwise thrust of the last heel against the shoe counter at 70 the point in the last pulling operation predetermined by the initial adjustment of said throw back plate.

The action of these parts in relation to the cycle of shoe and last separation will be 80 more clearly apparent from the diagrammatic showing of Figs. 2-5 inclusive of the drawings. In Fig. 2 the parts are shown in the position they occupy at the start of the last pulling operation, the shoe being 85 held between the opposed counter grippers and the heel pin 24 having been tilted to cramp and bind in the last by the initial downward movement of the plunger 30. In the movement of the parts from the position shown in Fig. 2 to that shown in Fig. 3, the resistance offered by the counter portion of the shoe to the lengthwise thrust of the last heel reacts through the bell crank lever, compressing the coiled spring 48 to reduce the lengthwise thrust of the last heel, at the same time swinging the abutment plate 50 outwardly so that by the 90 time the parts reach the position indicated in Fig. 3, the abutment plate 50 will 100 overlap the edge of the shelf 52 to a slight extent only. The abutment plate 50 will contact with the shelf, in the illustrated adjustment of the abutment plate, at a point in the last pulling operation before the bottom of the last heel clears the top of the shoe counter and when the forepart of the last will begin to exert substantial, and what at times has proved to be injurious, strain 105 upon the forepart of the upper approximately at the throat of the vamp or ball portion of the upper at for example, the point indicated at X in Figs. 3 and 4. When this point is reached, the contact of the rigid, unyielding plate 50 with the shelf 52 will 110 arrest positively further thrust-relieving compression of the spring 48 and will 115 momentarily and substantially augment the lengthwise thrust of the last heel against the counter portion of the shoe, relieving 120 very substantially the pressure against the throat of the vamp by giving the last a substantially increased lengthwise component of movement as illustrated in Fig. 4. The rearward swinging movement of the bell 125 crank lever effected by engagement with the plate 50 and shelf 52 will cause the abutment plate 50 to swing outwardly and over the edge of the shelf, as suggested in Fig. 4, so that the period during which the length- 130

wise thrust of the last heel is augmented, is substantially momentary only. As soon as the edge of the abutment plate 50 clears the edge of the shelf 52, the lengthwise thrust of the heel against the counter is relieved and with the clearance thus effected between the forepart of the last and the throat of the vamp (see Fig. 4) the last may now be further withdrawn downwardly and rearwardly from the shoe by the normal operation of the machine, without imposing injurious strains upon the shoe parts. The coiled spring 48 which has been compressed in the earlier portion of the last pulling operation, is effective as soon as the bottom of the last heel clears the top edge of the shoe counter to accelerate the lengthwise movement of the last, as suggested in Fig. 5 of the drawings. In the event a high shoe is being operated upon, as indicated in dotted lines of Figs. 2-5, the acceleration of the lengthwise movement of the last through the coiled spring 48 is of decided assistance in overcoming any additional resistance offered by the back stay portion of the top of the shoe which, in the usual operation of the machine, is folded back by the operator in mounting the last upon the spindle or heel pin.

30 The coiled spring 48 is useful in reducing the lengthwise thrust of the last during the early stages of its removal, during which time maximum strain is exerted against the parts of the shoe, and is useful also in accelerating the lengthwise movement of the last after the bottom of the last heel has cleared the top of the shoe counter. It is, however within the spirit of the present invention, to dispense with the coiled spring 48 and to adjust the unyielding abutment plate 50 to augment the lengthwise heelward thrust of the last at variably predetermined times in the last pulling operation. For example, it is possible, by adjustment of the plate 50, to cause augmented heelward thrust to the last at that time in the last pulling operation when the bottom of the last edge has cleared the shoe counter, or, so to adjust the abutment plate as to cause augmented heelward thrust of the last prior to this point as, for example, to relieve the strain against the forepart of the shoe upper in the manner previously described.

55 In the operation of the illustrated machine, the last with its shoe is mounted upon the heel pin 24 and is swung upwardly by the operator to position the shoe for co-operation with the counter grippers. When this has been done, the treadle 10 is actuated to start the power operation of the machine. As the cam shaft 12 begins to rotate, the counter grippers are closed upon the shoe and then the thrust bar 38 is actuated to depress the plunger 30, first cramping the heel

pin in the last and then pulling the last downwardly and rearwardly from the shoe, the spring 48, which is preferably employed, acting to reduce the initial lengthwise heelward thrust of the last against the shoe 70 counter and the abutment plate 50 subsequently acting to increase the lengthwise heelward thrust of the last at the point in the last pulling operation predetermined by the adjustment of the abutment plate 50, 75 after which the last is completely removed from the shoe, the carrier arm 26, dropping by gravity to the position shown in Fig. 1 and the counter grippers opening to release the shoe from which the last has been pulled, 80 at which point the machine is automatically stopped. The pulled last may now be removed from the heel pin and the machine is ready for operation upon the next shoe and last.

Having thus described my invention, what I claim as new and desire to secure by Letters Patent of the United States is:—

1. A machine of the class described having, in combination, shoe holding means, last holding means, mechanism for effecting relative movement of the said holding means, including movement lengthwise of the shoe and last to separate a shoe and its last, and unyielding abutment means arranged to co-operate with said mechanism at a determinate point in said relative separating movement to augment said relative lengthwise movement.

2. A machine of the class described having, in combination, shoe holding means, last holding means, mechanism for effecting relative movement of the said holding means, including movement lengthwise of the shoe and last to separate a shoe and its last, and unyielding abutment means arranged to co-operate with said mechanism at a determinate point in said relative separating movement momentarily to augment said relative lengthwise movement.

3. A machine of the class described having, in combination, shoe gripping means, last holding means, mechanism for effecting movement of the last holding means to move a last in a direction diagonally lengthwise heelward out of the shoe, and abutment means co-operating with said mechanism, at a determinate point in the last-removing movement of the last holding means positively to augment lengthwise thrust of the last.

4. A machine of the class described having, in combination, shoe gripping means, last holding means, mechanism for effecting movement of the last holding means to move a last in a direction diagonally lengthwise heelward out of its shoe, and abutment means co-operating with said mechanism at a determinate point in the last-removing movement of the last holding means.

mentarily to augment lengthwise thrust of the last.

5. A machine of the class described having, in combination, shoe holding means, last holding means, mechanism for effecting relative movement of said holding means including movement lengthwise of the shoe and last to separate a shoe and its last, and auxiliary means arranged to coöperate with 5 said mechanism at a determinate point in said relative separating movement to augment the relative lengthwise thrust of the last and shoe, said auxiliary means being constructed and arranged for adjustment to 10 vary the point in relative movement at which occurs said augmented relative lengthwise thrust.

6. A machine of the class described having, in combination, shoe holding means, last holding means, mechanism for effecting relative movement of said holding means including movement lengthwise of the shoe and last to separate a shoe and its last, and auxiliary means arranged to coöperate with 20 said mechanism at a determinate point in said relative separating movement momentarily to augment the relative lengthwise thrust of the last and shoe, said auxiliary means being constructed and arranged for 25 adjustment to vary the point in relative movement at which occurs said augmented relative lengthwise thrust.

7. A machine of the class described having, in combination, the shoe holding means, last holding means, mechanism for effecting relative movement of said holding means to separate a shoe and its last, and auxiliary means coöoperating with said mechanism during the initial portion of the period of relative vertical movement of the last heel and shoe counter to clear each other to cause 35 relative lengthwise thrust of the last heel and shoe counter and subsequently at a determinate point in said period positively to 40 augment said thrust.

8. A machine of the class described having, in combination, shoe holding means, last holding means, mechanism for effecting relative movement of said holding means to 50 separate a shoe and its last, and auxiliary means coöoperating with said mechanism during the initial portion of the period of relative vertical movement of the said last heel and shoe counter to clear each other to cause 55 relative lengthwise yielding thrust of the last heel and shoe counter and subsequently at a determinate point in said period to cause positive relative thrust of the last heel and shoe counter.

60. 9. A machine of the class described having, in combination, shoe gripping means, last holding means, mechanism for effecting movement of the last holding means to move a last out of its shoe in a generally diagonally heelward direction causing lengthwise 65

thrust of the last heel against the shoe counter, and auxiliary means coöoperating with said mechanism during the initial portion of the movement of the last heel to clear the shoe counter to cause lengthwise thrust 70 of the last heel against the counter and subsequently at a determinate point in said movement positively to augment the lengthwise heelward thrust of the last.

10. A machine of the class described, having, in combination, shoe holding means, last holding means, mechanism for effecting relative movement of said holding means to separate a last and shoe including movement causing relative lengthwise thrust of the last 75 heel and shoe counter, means coöoperating with said mechanism during the initial portion of the period of movement of the last heel and shoe counter to clear each other arranged to yield responsively to the resistance offered by the counter to said lengthwise thrust of the last heel to cause a thrust, and means subsequently operative at a determinate point in said period positively to arrest said yield and positively to augment the 80 relative lengthwise thrust of the last and shoe.

11. A machine of the class described having, in combination, shoe holding means, last holding means, mechanism for effecting relative movement of said holding means to separate a last and shoe including movement causing relative lengthwise thrust of the last heel and shoe counter, means coöoperating with said mechanism and arranged to act 95 responsively to the resistance offered by the shoe to said lengthwise thrust of the last during the initial portion of the period of movement of the last heel and shoe counter to clear each other to cause a thrust, and 100 abutment means subsequently operative at a determinate point in said period positively to arrest said yield and positively to augment the relative lengthwise thrust of the last and shoe.

12. A machine of the class described having, in combination, shoe holding means, last holding means, mechanism for effecting relative movement of said holding means to separate a last and shoe including movement 115 causing relative lengthwise thrust of the last heel and shoe counter, a spring coöoperating with said mechanism and arranged to yield responsively to the resistance offered by the shoe to said lengthwise thrust of the last 120 during the initial portion of the period of movement of the last heel and shoe counter to clear each other to cause a thrust, and abutment means subsequently operative at a determinate point in said period to arrest 125 said yield and positively to augment the relative lengthwise thrust of the last and shoe, said abutment means being constructed and arranged for adjustment to vary the point during said period at which said yield 130

- is arrested and the relative lengthwise thrust augmented.
13. A machine of the class described having, in combination, shoe gripping means, last holding means, mechanism for effecting movement of the last holding means to move the last from the shoe in a generally diagonally rearward direction, a stationary abutment member, and a relatively movable member coöperating with said stationary member and said last holding means at a determinate point in the removal of the last from its shoe to augment positively the lengthwise heelward thrust of the last.
14. A machine of the class described having, in combination, shoe gripping means, last holding means, mechanism for effecting movement of the last holding means to move the last from the shoe in a generally diagonally rearward direction, a stationary abutment member, and a relatively movable member coöperating with said stationary member and said last holding means at a determinate point in the removal of the last from its shoe momentarily to augment the lengthwise heelward thrust of the last.
15. A machine of the class described having, in combination, shoe gripping means, last holding means, mechanism for effecting movement of the last holding means to move the last from the shoe in a generally diagonally rearward direction, a stationary abutment member, and a relatively movable member coöperating with said stationary member and said last holding means at a determinate point in the removal of the last from its shoe to augment positively the lengthwise heelward, thrust of the last, said relatively movable member being constructed and arranged for adjustment variably to predetermine the point in the pulling operation of said augmented thrust of the last.
16. A machine of the class described, having, in combination, shoe gripping means, last holding means, mechanism for separating the shoe and last by relative movement of the last holding means and shoe gripping means having a component of movement lengthwise of the shoe, and auxiliary means coöperating with said mechanism in the separation of the shoe and last momentarily to increase the relative lengthwise movement at a determinate point in the last and shoe separating movement.
17. A machine of the class described, having, in combination, shoe gripping means, last holding means, mechanism for separating the shoe and last by relative movement of the last holding means and shoe gripping means having a component of movement lengthwise of the shoe, and auxiliary means coöperating with said mechanism in the separation of the shoe and last and arranged for adjustment to increase the rela-

tive lengthwise movement at variably predetermined points in the last and shoe separating movement.

18. A machine of the class described having, in combination, shoe gripping means, last holding means, mechanism for moving the last holding means to move the last from the shoe in a direction having a component lengthwise heelward of the shoe, and auxiliary means coöperating with said mechanism and arranged for adjustment to increase the lengthwise last movement at variably predetermined points in the last pulling movement of said mechanism.

19. In a machine of the class described, in combination, shoe gripping means, a last pulling plunger, a lever carried by and bodily movable with the plunger, a last carrier connected to said lever arranged upon movement of the plunger to remove the last from a gripped shoe in a direction substantially perpendicular to the plane of the shoe bottom with a component of movement lengthwise heelward of the shoe, and auxiliary means operative at a determinate point in the last pulling movement of the plunger positively to augment the lengthwise movement of the last.

20. In a machine of the class described, in combination, shoe gripping means, a last pulling plunger, a lever carried by and bodily movable with the plunger, a last carrier connected to said lever arranged upon movement of the plunger to remove the last from a gripped shoe in a direction substantially perpendicular to the plane of the shoe bottom with a component of movement lengthwise heelward of the shoe, and abutment means coöperating with said lever and operative at a determinate point during last pulling movement of the plunger to move said lever in a direction positively to augment the lengthwise movement of the last.

21. In a machine of the class described, in combination, shoe gripping means, a last pulling plunger, a lever carried by and bodily movable with the plunger, a last carrier connected to said lever arranged upon movement of the plunger to remove the last from a gripped shoe and auxiliary means operative at a determinate point in the last pulling movement of the plunger momentarily to augment the lengthwise movement of the last.

22. In a machine of the class described, in combination, shoe gripping means, a last pulling plunger, a bell crank lever mounted on and bodily movable with the plunger, a last carrier pivotally connected to said lever arranged upon movement of the plunger to remove the last from a gripped shoe, a stationary abutment, and means in operative connection with said lever arranged to engage said abutment at a determinate point

in the last pulling movement of the plunger to move said lever in a direction to augment the lengthwise movement of the last.

23. In a machine of the class described, in combination, shoe gripping means, a last pulling plunger, a bell crank lever mounted on and bodily movable with the plunger, a last carrier pivotally connected to one arm of said lever arranged upon movement of the plunger to remove the last from a gripped shoe, and auxiliary means comprising a stationary abutment and a movable coöperating abutment connected to the other arm of said lever and arranged to engage said fixed abutment at a determinate point in the last pulling movement of the plunger positively to cause said bell crank lever to swing in a direction to augment the lengthwise movement of the last.
24. In a machine of the class described, in combination, shoe gripping means, a last pulling plunger, a bell crank lever mounted on and bodily movable with the plunger, a last carrier pivotally connected to one arm of said lever arranged upon movement of the plunger to remove the last from a gripped shoe, a rod pivotally connected at one end to the other arm of said lever, a guide carried by and movable with said plunger and through which the other end of said rod slides, a stationary abutment, a co-operating abutment mounted on said rod intermediate of its ends and arranged to engage said stationary abutment during last pulling movement of the plunger, and a coiled spring sleeved on said rod between said guide and abutment and arranged yieldingly to resist swinging movement of said bell crank lever in one direction.
25. In a machine of the class described, in combination, shoe gripping means, a last pulling plunger, a bell crank lever carried by and bodily movable with said plunger, a last carrier pivoted to one arm of said lever, a guide carried by and movable with said plunger, a rod pivoted at one end to the other arm of said lever and freely slideable in said guide, a stationary abutment, a co-

operating abutment member adjustably mounted on said rod and arranged, during last pulling movement of the plunger, partially to overlap said stationary abutment for sliding engagement therewith momentarily to swing said lever and last carrier in a direction to augment the lengthwise movement of the last.

26. An organized machine for pulling lasts from their shoes having, in combination, shoe holding means, last holding means and mechanism organized to operate the last holding means to pull the last in a direction generally diagonally heelward of the shoe, means constructed and arranged momentarily and positively to augment lengthwise thrust of the last heel against the counter portion of the shoe.

27. An organized machine for pulling lasts from their shoes having, in combination, shoe holding means, last holding means, and mechanism organized to operate the last holding means to pull the last in a path generally diagonally heelward of the shoe, means arranged for adjustment and effective to augment lengthwise thrust of the last at that point in the last pulling operation predetermined by adjustment of said means.

28. An organized machine for pulling lasts from their shoes having, in combination with shoe holding means last holding means and mechanism organized to operate the last holding means to pull the last from its shoe including movement of the last causing lengthwise thrust of the last heel against the shoe counter, of auxiliary means co-operating with said mechanism and effective to cause lengthwise thrust of the last heel responsively to the resistance offered thereto by the shoe counter during the first portion of the movement of the last heel to clear the counter, and effective subsequently positively to augment the lengthwise thrust of the last heel against the counter to relieve the strain against the forepart of the shoe.

In testimony whereof I have signed my name to this specification.

JOHN H. RICHARDSON.

Certificate of Correction.

It is hereby certified that in Letters Patent No. 1,398,344, granted November 29, 1921, upon the application of John H. Richardson, of Melrose Highlands, Massachusetts, for an improvement in "Last-Pulling Machines," an error appears in the printed specification requiring correction as follows: Page 7, line 2, claim 22, before the word "to", first occurrence, insert the word *positively*; and that the said Letters Patent should be read with this correction therein that the same may conform to the record of the case in the Patent Office.

Signed and sealed this 16th day of May, A. D., 1922.

[SEAL.]

KARL FENNING,

Acting Commissioner of Patents.
